US0D1045128S

(12) **United States Design Patent** (10) **Patent No.:** **US D1,045,128 S**
(45) **Date of Patent:** **** Oct. 1, 2024**

(54) **MODULAR CONCOURSE**

(71) Applicants: **William Daniel Ochse**, Burlingame, CA (US); **Eugene C. Lewis**, Burlingame, CA (US)

(72) Inventors: **William Daniel Ochse**, Burlingame, CA (US); **Eugene C. Lewis**, Burlingame, CA (US)

(**) Term: **15 Years**

(21) Appl. No.: **29/799,253**

(22) Filed: **Jul. 13, 2021**

(51) LOC (14) Cl. **25-01**

(52) U.S. Cl.

USPC **D25/3**; D25/1; D25/22; D25/32

(58) **Field of Classification Search**

Primary Examiner — T Chase Nelson

Assistant Examiner — Sydney Margaret Parsley

(74) Attorney, Agent, or Firm — Theodore J. Bielen, Jr.

(57) **CLAIM**

The ornamental design for a modular concourse, as shown and described.

DESCRIPTION

FIG. 1 is a top, front, left side perspective view of a modular concourse showing our new design;

FIG. 2 is a right side elevational view thereof;

FIG. 3 is a left side elevational view thereof;

FIG. 4 is a front elevational view;

FIG. 5 is a rear elevational view thereof;

FIG. 6 is a top plan view; and,

FIG. 7 is a bottom plan view.

1 Claim, 4 Drawing Sheets
